Application June 12, 1944, Serial No. 539,863
3 Claims. (Cl. 254—131)

This invention relates to tools and more particularly to a type of tool adapted to facilitate the removal of wrist-pins adapted to hold the pistons and connecting rods of gasoline engines in related assembly.

A primary object of this invention is the provision of a tool adapted to ease the tensional engagement of a portion of a connecting rod engaging a wrist-pin to hold the connecting rod and a piston in related assembly, whereby the wrist pins and hence the crank shaft of a gasoline engine may be readily disassembled.

An additional object of this invention is the provision of a tool adapted to facilitate the removal and replacement of such a wrist-pin without the necessity of removing the cylinder head of the engine.

A still further object is the provision of such a tool which will be reliable in operation, sturdy and durable in construction, and relatively simple and inexpensive to manufacture.

As conducive to a clearer understanding of this invention it may here be pointed out that in conventional gasoline engines the ends of the connecting rods are provided with wrist-pin clamps comprised of a circular portion adapted to surround the wrist-pin and extending split lugs, each having an aperture therethrough, one of which has a smooth bore and the other of which is threaded, a screw being adapted to pass through the smooth bore and engage the threaded bore and when tightened to hold the clamps tightly about the wrist-pin. The ends of the wrist-pin are journaled for rotative movement in the side walls of the piston. As removal and replacement of the wrist-pins occurs very infrequently, perhaps no more than once in several years, it frequently happens that even after removal of the screw holding the clamp together the clamp has become set and retains a relatively tight grip on the wrist-pin, making removal thereof extremely difficult, unless the cylinder head is completely removed and the piston brought upwardly through the cylinder to a position wherein it may be driven out with a hammer, for example. A primary object of this invention, therefore, is the provision of a tool which will release the relatively tight engagement of the clamp on the connecting rod with the wrist-pin, under such conditions, whereby the pin may merely be pushed out when the piston is moved to its lowermost position in the cylinder.

Other objects will in part be obvious and in part be pointed out as the description of the invention proceeds.

Application June 12, 1944, Serial No. 539,863

3 Claims. (Cl. 254—131)

Having reference now to the accompanying drawings wherein there is shown a preferred form of this inventive concept:

Figure 1 is a side elevational view of one form of device of the instant invention shown in association with a piston and connecting rod, certain parts being broken away and certain other parts being shown in section.

Figure 2 is a view similar to Figure 1 but showing the operating parts of the tool in a different position of adjustment.

Figure 3 is a front elevational view of the tool shown in Figures 1 and 2, and

Figure 4 is a detailed sectional view of certain of the operating parts of the mechanism.

Like reference numerals refer to like parts throughout the several views of the drawings.

Having reference now to the drawings, and more particularly to Figures 1 and 2, a connecting rod 10 of conventional type has at its lower extremity a bifurcated portion 11 forming a semi-cylindrical recess 12, adapted to engage a crankshaft (not shown). Extending from portion 11 outwardly, are two projections 13 through which are passed vertical bores 14 adapted for the engagement of screws holding the conventional lower clamp (not shown), to secure the connecting rod to the crankshaft. The upper end of connecting rod 10 terminates in an enlarged portion 15 having a centrally disposed circular aperture 16 therethrough adapted to surround a wrist-pin 17. The outer ends of wrist-pin 17 are journaled, in the conventional manner, in the side walls of a piston 18. Portion 15 is split as at 19, and has extending from opposite sides of the split portion a pair of projecting lugs 20 and 21, each of which has an aperture therethrough. The aperture 22 in lug 21 is smooth, while the aperture 23 in lug 20 is threaded. Thus the passage of a headed screw through aperture 22 into threaded engagement with aperture 23 and tightening of the same will result in a clamping action holding the connecting rod 10 and wrist-pin 17 securely in related assembly.

The mechanism hereinbefore described is all conventional and has been described merely to show the operating parts upon which the tool of the instant invention acts.

Having reference now to the tool, generally indicated at 25, comprising the instant invention, a bar preferably cylindrical in configuration and of a suitable metal, is formed to provide a handle portion 26, bent inwardly as at 27, bent upwardly as at 28, and bent outwardly in a slight curve as at 29. The upper outwardly curved portion

29 terminates in a flat or ball-shaped portion 30 of a diameter adapted to pass through smooth bored aperture 22 but insufficient to pass through threaded aperture 23 and hence adapted under conditions to be hereinafter described to seat it self in the mouth of threaded aperture 23.

A member generally indicated at 35 comprised of a cylindrical body portion 36 (see Figure 4), and bifurcated at its upper extremity to provide a pair of extending legs 37 and 38 (see Figure 3), is pivotally secured to portion 27 of rod 25 as by means of a rivet 39 passed through suitable apertures in legs 37 and 38 and portion 27. The lower portion of member 35 is provided with a threaded aperture 40 therein, adapted to engage a screw 41 having a cylindrical head 42.

From the foregoing the operation of the device should now be readily understandable. Piston 18 is first moved to its lowermost position in its associated cylinder, or until the ends of wrist-pin 17 and their associated apertures in the piston wall are clear of the cylinder wall. The screw clamping lugs 20 and 21 together is then removed and the tool 25 placed in the position shown in Figure 2, that is, with flattened head 30 passed through aperture 22 and with the ball-shaped head 42 of screw 41 seated in the upper portion of aperture 14. Movement of the parts to the position shown in Figure 1 will now cause head 30 to press against lug 20, thus separating lugs 20 and 21 and causing a release of the tight grip of the clamping means on wrist-pin 17, which now may be removed from the piston and connecting rod by a simple pressure of the fingers on one end thereof. Member 35 is pivoted to rod 25 in such position that when the parts are moved to the position shown in Figure 1 it is rotated just past the center of pressure, whereby it will remain in the position thus assumed, leaving both hands free for removal of wrist-pin 17 if necessary. Screw 41 is provided so that the pressure exerted to separate the lugs may be varied by altering the effective length of the composite member comprised of member 35 and screw 41. The device may, of course, be made in a variety of shapes and sizes to accommodate any desired type or manufacture of cylinder, piston and connecting rod.

From the foregoing it will now be seen that there is herein provided a tool accomplishing all the objects of this invention and many others including advantages of great practical utility and commercial importance.

As many embodiments may be made of this inventive concept, and as many modifications may

be made in the embodiment herein shown and described it is to be understood that all matter hereinbefore set forth is to be interpreted merely as illustrative and not in a limiting sense.

5 I claim:

1. In a tool for releasing the grip of a connecting rod clamp having projecting lugs with apertures therethrough, one of said apertures being threaded and the other being smooth and of greater diameter than said threaded aperture, on a wrist-pin; the combination of a curved rod, an end portion of said rod being of a diameter sufficient to pass through said second aperture but not said first aperture, and a member adapted to be seated on a portion of said connecting rod, pivoted to said curved rod at an intermediate point, whereby pressure on one end of said curved rod will exert a leverage through said member on said end portion to separate said lugs.

10 2. In a tool for releasing the grip of a connecting rod having projecting lugs with apertures therethrough, one of said apertures being threaded and the other being smooth and of greater diameter than said threaded aperture, on a wrist-pin; the combination of a curved rod, an end portion of said rod being of a diameter sufficient to pass through said second aperture but not said first aperture, a member adapted to be seated on a portion of said connecting rod, pivoted to 15 said curved rod at an intermediate point whereby pressure on one end of said curved rod will exert a leverage through said member on said end portion to separate said lugs, and means for varying the effective length of said member to 20 vary the pressure exerted on said lug having said threaded aperture therethrough.

25 3. In a tool for releasing the grip of a connecting rod clamp having projecting lugs with apertures therethrough, one of said apertures being threaded and the other being smooth and of greater diameter than the threaded aperture, on a wrist-pin, the combination of a curved rod, an end portion of said rod being of a diameter sufficient to pass through said second aperture but not said first aperture, a member having a threaded aperture in its lower extremity, a screw rotatably engaged in said aperture to vary the effective length of said member, a head on said screw adapted to be seated on a portion of said connecting rod, and a pivot securing said member to said curved rod at an intermediate point whereby pressure on one end of said curved rod exerts a leverage through said member and said head on said end portion to separate said lugs.

55 EUGENE T. DAUBS.
